ATTORNEYS.

UNITED STATES PATENT OFFICE.

LOUIS ZECKENDORF, OF NEW YORK, N. Y.

DESIGN FOR A LEAD-PENCIL.

SPECIFICATION forming part of Design No. 16,032, dated January 24, 1888.

Application filed December 13, 1887. Serial No. 957,824. Term of patent 14 years.

To all whom it may concern:

Be it known that I, LOUIS ZECKENDORF, of the city, county, and State of New York, have invented a new and original Design for Lead-Pencils, of which the following is a full, clear, and exact specification.

Reference is to be had to the accompanying drawing, forming a part of this specification, and in which is illustrated in perspective my 10 newly-designed lead-pencil.

My design consists in a pencil having the flat transversely-converging side surfaces, *a a*, and transversely-convexed top surface, *b*, when viewed from either end or in perspective, the 15 convergence of the side surfaces, *a a*, being regular and their vertex *c* being opposite the

center of the curved top surface, *b*, and the surfaces all being regular and non-convergent longitudinally.

Having thus described my invention, what I 20 claim as new, and desire to secure by Letters Patent, is—

The design for a lead-pencil shown and described, the same consisting of the flat transversely-converging side surfaces, *a a*, and 25 transversely-convexed top surface, *b*, all the surfaces being regular and non-convergent longitudinally.

LOUIS ZECKENDORF.
